UNITED STATES PATENT OFFICE

2,480,365

KNIFE

Howard E. Harson, Oak Lawn, Ill.

Application February 18, 1946, Serial No. 648,278

3 Claims. (Cl. 30—163)

1

This invention relates to knives, the primary object of the invention being to provide a knife wherein the blade thereof moves longitudinally of the handle, when it is retracted or extended, the movement of the blade being controlled by the manner in which the knife is held in the hand of the operator, that is to say, if the blade is to be extended, the handle is held with the open end down, to allow the blade to gravitate therefrom, and if the blade is to be retracted, the handle is held so that the blade will gravitate to its position within the handle.

An important object of the invention is to provide a knife of this character which will be securely held in either its extended or retracted positions, the blade-holding means constituting a flexible arm which may be readily operated to disengage the blade to permit of the movement of the blade into and out of the handle.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing

Figure 1 is a side elevational view of a knife constructed in accordance with the invention.

Figure 2 is a longitudinal sectional view through the knife with the blade retracted.

Figure 3 is a longitudinal sectional view through the knife taken at right angles to Fig. 2.

Figure 4 is a sectional view taken on line 4—4 of Fig. 3.

Referring to the drawing in detail, the knife handle is indicated generally by the reference character 5, the knife handle being provided with a central longitudinal opening extending throughout the length of the handle.

The longitudinal opening of the handle is preferably rectangular in formation, to conform to the shape of the inner end of the knife blade 12, which is also rectangular, as clearly shown by Fig. 2 of the drawing.

Positioned within the opening of the knife handle, and secured thereto by means of the pins 6, are plates 7 which plates have their forward ends extended laterally as at 8 where they overlie the ends of the handle 5. These plates 7 are formed with elongated openings 9, these openings of the plates 7 being disposed opposite to each

other, to accommodate the circular studs 10 that extend from the head 11 of the blade 12.

Also mounted within the opening of the handle, is a lever 13 which embodies a length of spring steel or other suitable material, the width of the lever being such that it will rest on the plate 7 adjacent thereto. As shown, the ends of the lever 13 are reduced and extended at right angles, providing stops 14, which stops are adapted to engage the stud 10 disposed on the side of the blade, with the lever 13, to hold the blade in its extended or retracted position.

As clearly shown by Fig. 2 of the drawing, a button 15 is secured to the lever, at a point intermediate its ends, the button extending through the opening 16 formed in the handle, so that it may be engaged by the thumb of the person using the knife, to operate the lever. The lever 13 is bowed at a point intermediate its ends, so that when the button 15 is pressed, the ends of the lever, are tilted upwardly until the stops 14 thereof disengage the stud 10. This releases the blade for movement longitudinally of the handle, and if it is desired to extend the blade, the handle will be held with the open end down, whereupon the blade will gravitate to its open position.

When the blade is in its open position, the stop 14 adjacent to the open end of the handle will contact the stud 10 holding the blade in its extended position, the stud engaging the walls of the elongated openings of the plates 7. When it is desired to retract the blade, the button 15 is pressed causing the ends of the lever 13 to move to the dotted line positions as shown by Fig. 2 of the drawing. The handle is now held with the open end up, whereupon the blade will move into the handle by gravity.

It might be further stated that the plates 7 are formed with reduced ends 17 which are bent into engagement with each other, providing a loop 18 into which a suitable strap or carrying chain may be extended, should it be desired to carry the knife in this manner.

From the foregoing it will be seen that due to the construction shown and described, I have provided a knife which when gripped and the button 15 pressed in a manner as described, will cause the blade to be released so that it may be readily extended. This operation can be accomplished with one hand, and the blade extended or retracted by tilting the handle, as previously described, leaving the other hand free.

What is claimed is:

1. A knife embodying a hollow handle, guide plates within the handle, said guide plates being

disposed in spaced relation with respect to each other, a blade movable between the guide plates, studs extending from the blade, said guide plates having openings elongated longitudinally of the guide plates, said studs being disposed within the openings, a spring lever bowed intermediate its ends mounted within the handle, extensions on the ends of the spring lever, the extensions being disposed within the elongated opening of one of the guide plates engaging one of the studs of the blade for restricting movement of the blade, and means for flexing the spring lever intermediate its ends moving the ends of said lever outwardly, disengaging the stud and permitting movement of the blade longitudinally of the handle.

2. A knife embodying a hollow handle, spaced guide plates disposed within the handle, said guide plates having elongated openings, a knife blade disposed between the guide plates, studs on the knife blade, said studs being disposed within the elongated openings of the plates for guiding the blade in its movements longitudinally of the handle, a spring-operating lever disposed within the handle between one of the plates and the handle, reduced inturned end members on the lever, the reduced end members being extended through the elongated openings in one of said guide plates, one of the inturned end members engaging one of the studs of the blade for normally holding the blade within the handle, the opposite end member lying in spaced relation with one end wall of the elongated opening, and adapted to engage the other one of said studs forcing the stud into engagement with the end wall, to restrict outward and inward movement of the blade, and means for moving the operating

lever to disengage the studs and release the blade for movement longitudinally of the handle.

3. A knife embodying a hollow handle, guide plates mounted within the handle and disposed in spaced relation with respect to each other, said guide plates having openings elongated longitudinally thereof, a blade movable between the guide plates, studs on the blade, said studs being disposed within the elongated openings of the guide plates, a spring lever curved intermediate its ends, fitted within the handle and resting on one of the guide plates, extensions at the ends of the lever and being disposed within the opening of one of the guide plates and adapted to engage one of the studs of the blade restricting movement of the blade within the handle, said handle having an opening intermediate its ends, a button connected with the lever intermediate its ends and extending through the opening to be engaged by the operator in forcing the intermediate portion of the lever inwardly, whereby the ends of said lever are moved away from the blade to disengage the stud of the blade with which it engages.
